DESIGN FOR A DRAWER HANDLE

Alvin S. Rummelsburg, Hempstead, N. Y.

Application February 19, 1948, Serial No. 144,598

Term of patent 3½ years

(Cl. D10—8)

To all whom it may concern:

Be it known that I, Alvin S. Rummelsburg, a citizen of the United States of America, residing in East Rockaway, Hempstead, county of Nassau, and State of New York, have invented a new, original, and ornamental Design for a Drawer Handle, of which the following is a specification, reference being had to the accompanying drawing, forming part thereof, wherein:

I claim:

The ornamental design for a drawer handle, substantially as shown.

ALVIN S. RUMMELSBURG.
